Elbridge Edgars (and) Isaac H. Edgars
Wayne Co. Ohio

Letters Patent.

The Schedule referred to in these Letters Patent and manufacturing
of the same containing a description in the words of the said Elbridge
Edgar and Isaac H. Edgar themselves of their improvement in their
Spike Thrusting machine.

To all to whom these presents shall come:—We, Elbridge
Edgar and Isaac H. Edgar of the County of Wayne and
State of Ohio have invented a new and useful improvement in
Spike Thrusting machine, and that the following is a full and
exact description of the construction of the said machine as inven-
tored by us. The machine is constructed in the following man-
ner.—The same consists of 4 posts, about 4 inches square
and 2 side posts 13 inches wide and 2 ins thick. The side posts are
framed into the inside of the posts 18 ins from the bottom and
secured to them with screw bolts passing through both. The front
posts stand at right angles with the side posts. The lower ends
of the back posts are inclined backwards to an angle of about 20
degrees from the parallel of the front posts. The posts are 19 ins
apart at the tops of the side posts 44 ins in width of the upper edge
of the side posts is 3 feet 6 in long, projecting 6 ins in front of
the same distance back of the posts. The lower part of the posts
extend 2 ins on the outside of the posts and are all parallel
with them. A cap is framed across on the top of the front
posts immediately above the side posts. The back posts extend
about 3 ins above the side posts with a cap framed across on
the top of them. Two cross posts 2 by 4 ins in size are framed
into the back and front of the frame near the bottom of the
posts. The frame made 2 feet 6 ins in the clear between the

side girls - the concave consists of 2 pieces 2 feet 6 ins long and 2 ft 7 $\frac{1}{2}$ ins thick. The lower piece 3 ins wide on the upper side which is made concave and forms an arc of a circle, the radius of which is 9 ft $\frac{1}{4}$ ins. The concave part of the upper piece is of the same dimensions and shape as the lower piece. The back part is made wide enough to extend nearly to the back of the frame. It is made the proper slope and used as part of the feed apron, the concave commences immediately under the centre of the cylinder and extends toward the back of the frame. The concave is supported at each end in a rabbet formed on the inside of the side girls, by cutting such a board to fit the upper and under sides of the concave and making them fast to the side girls. The concave contains about 48 spikes, made and placed in the following manner. That part of the spikes which extends above the surface of the concave is 18 $\frac{1}{2}$ ins long, $\frac{5}{8}$ of an inch square at the surface of the wood and $\frac{1}{4}$ of an inch square at the point, sloping them equal on the 2 sides and making the slope all on the back side to bring them to the shape above described. Giving the front side a height ^{the same height as the back side, so that the front side is higher than the back side} one full row of 17 spikes is placed near the lower edge of the lower concave piece an equal distance apart, another half row is placed near the upper edge of the same piece the spikes in the half row are placed exactly above the alternate spikes in the lower row. 2 half rows like the one just described are placed in the upper piece. The spikes in each row placed so as to stand above the spaces in the row next below. Both pieces of the concave are covered with sheet iron. An apron extends from the lower part of the concave in a horizontal direction to the front end of the girls, and rests on a board which fills the space between the above apron and the apron below and answers for a brace to the frame. The lower end of the feed apron joins the upper edge of the concave, and rests on a small board framed into the top of the side girls near the back end an inch board is placed on the front end of the side girls and fills the space between the front cap and the end of the side girls and prevents the grain

from rising too high as it passes out of the machine. Semi-circular pieces are placed on the side-girts between the posts and cut to a curve of 10 in. radius from the centre of the cylinder. That part of this circle between the girts is covered with sheet iron which forms a cap over the cylinder. The cylinder-shaft is made of 1 1/8 in. square bar iron 3 feet 10 in. long, with 2 journals 30 in. apart, and 6 in. to project on the outside of the journal at one end to receive the pulley. The journal each 2 in. long and 1 1/8 in. diameter. These journals run in boxes of cast iron or some other suitable material placed in the top of the side-girts in the centre between the front and back posts. on this shafts and between the journals are placed 23 heads, 15 in. diameter and 1 1/4 in. thick, one in the centre and one at each end near the journals. The heads are put on the shaft with cast iron centers made with flanges which are riveted to the head. on the surface of the heads and lengthwise of the cylinder are placed six pieces of lagging 29 1/2 in. long. The width of the surface of each piece is $\frac{1}{16}$ part of the circumference of the heads, they are 2 in. thick and let this whole thickness into the heads. in each piece of lagging there are 16 spikes in a half row so that each 2 pieces constitutes a whole row. The spikes in one row following the spaces in the other so as to fill the spaces in the lower row of the concaves. That part of the cylinder spikes which extend beyond the surface of the lagging are the same length and shape of the spikes in the concave. The sloped side of the spikes are set to run foremost as the cylinder revolves. The other end is 2 1/2 inches long, made tapering with a slant cut on the end to receive a burr. The spikes are put through the lagging and the burr struck on the inside to prevent the spike from being thrown out by centrifugal force and to make it convenient to replace spikes which may be injured or broken by accident. The lagging is covered with sheet iron. The ends of the cylinder are secured with sufficient

bands. The middle of the banding secured to the head by some bolts passing through the center of the cylinder.

Improvements claimed. We claim as our improvement the following construction of the frame of this machine which is cheap, convenient and durable also the form of the cylinder with spikes of wood or lathing on the surface, and the spikes passing through them with some and bars on the inside. The spikes are straight on one side and sloped on the other sides. The side most sloped is placed so as to roll on the grain, the construction of the cylinder is such that while it possesses sufficient strength to be durable, it has no unnecessary weight and consequently requires less power to propel it than most of those now in use. The shape of the spikes is such that when they are set in the cylinder, the points motion backwards which causes the straw to leave the cylinder as soon as it passes the concave and prevents it from passing round and clogging the cylinder. These spikes being placed in wood are less liable to be broken or injured than when placed in iron. All the above improvements we rely on together with the privilege to vary the proportion and material according to the law.
